UNITED STATES PATENT OFFICE

BRADLEY HOAL, OF PARKERSBURG, WEST VIRGINIA

ROLLER BEARING FOR DRAWERS

Application filed December 10, 1929. Serial No. 413,118.

This invention relates to roller bearings for drawers and more particularly to bearings of this type that embody casings adapted to be recessed into the guides for the drawers, and rollers supported in the casings by anti-friction balls.

The invention has for one of its objects to provide a bearing of the character stated wherein the anti-friction balls shall be supported by the casing in a manner to reduce the frictional contact between these parts to the minimum and in a manner to prevent the weight of the drawer from setting up a binding action between the roller and the anti-friction balls, whereby to insure the free movement of the roller and consequently the easy movement of the drawer.

The invention has for a further object to provide a bearing of the character stated wherein the bottom of the casing shall be of such angular formation in cross section as to provide, in cooperation with the sides of the casing, races having straight walls and adapted to maintain the anti-friction balls in straight rows at opposite sides of the axis of the roller.

The invention has for a further object to provide a bearing of the character stated wherein the casing shall be of such formation as to permit it to fit closely in the corner of a drawer guide.

With the foregoing and other objects in view, the nature of which will appear as the description proceeds, the invention consists in the construction, combination and arrangement of parts hereinafter fully described and claimed, and illustrated in the accompanying drawing wherein:

Figure 1 is a sectional view illustrating the manner in which roller bearings constructed in accordance with my invention are to be used in connection with the drawer of an article of furniture;

Figure 2 is a sectional view taken on a vertical plane extending longitudinally and centrally through the bearing;

Figure 3 is a sectional view taken on a vertical plane extending centrally and transversely through the bearing;

Figure 4 is a top plan view of the bearing, and

Figure 5 is a view partly in vertical section and partly in side elevation of a slightly modified form of the bearing.

The bearing comprises a casing 1 which is made of light sheet metal and is fully open at its upper end. The casing 1 is of elongated rectangular formation in plan, and is provided at its upper end with an outer flange 2 which is of substantially elliptical formation in plan, one edge of the flange being flat and arranged in close proximity to the adjacent end of the casing. A plate 3 is arranged within the casing 1 above the lower end of the latter. The plate 3 contacts with the sides 4 and ends 5 of the casing 1, and it is supported within the casing by tongues 6, the tongues forming integral parts of the sides of the casing and contacting with the bottom of the plate.

The plate 3 is of angular formation in cross section, and presents race elements 7 which incline downwardly in opposite directions from the longitudinal center of the plate to the sides 4 of the casing 1. The race elements 7 are flat and cooperate with the flat sides 4 of the casing 1 to provide races for anti-friction balls 8. The races are of angular formation in cross section and extend longitudinally of the casing 1 at opposite sides of the vertical longitudinal center thereof, with the result that the balls 8 are supported in rows at opposite sides of said center. As the walls of the races are flat, the contact between the balls 8 and the races is so slight as to permit the balls to be freely rotated. The plate 3 is provided at its ends with upstanding flanges 9 between which the balls 8 are arranged and which serve to maintain the balls out of contact with the ends 4 of the casing 1.

A roller 10 is arranged within the casing 1 upon the balls 8, and it is supported by the balls with its upper surface arranged slightly above the flange 2 of the casing. A pin 11, which passes through the roller 10 and has its ends arranged in openings 12 in the ends 5 of the casing 1, holds the roller against upward displacement from the cas-

ing. In Figure 5 there is shown a slight modification of the means for securing the roller 10 and the casing 1 against upward displacement therefrom, this means consisting of conical lugs 13 carried by the ends 5 of the casing 1 and fitting in similar recesses 14 in the ends of the roller 10. The lugs 13 are preferably formed integrally with the ends 5 of the casing 1, and are provided by forcing portions of the ends of the 10 casing inwardly.

The manner in which bearings embodying my invention are adapted to be used is shown in Figure 1 wherein 15 designates the sides, 16 the top and 17 the drawer of an article of furniture. The drawer is supported by guides 18 and 19 and the bearings are recessed into the guides in a manner to permit the drawer 17 to rest upon the rollers 10. As the flange 2 has one flat end, and as such end is arranged in close proximity to an end of the casing 1, the bearings applied to the guides 18 may be arranged closely in the corners of these guides. As the anti-friction balls 8 have the minimum of contact with their races, and as the races of each bearing support the anti-friction balls in straight lines at opposite sides of the longitudinal center of the roller, the weight of the drawer 17 will not set up a binding action between the rollers and the anti-friction balls, with the result that the drawer is supported for easy inward and outward movement.

If desired, the rear side 20 of the drawer 35 may be provided with a bearing so arranged that the roller 10 thereof will contact with a strip 21 secured to the under side of the top 16 should the drawer be tilted during its outward movement.

It should be apparent from the foregoing 40 description, taken in connection with the accompanying drawing that the bearing is simple, durable and highly efficient, that it may be manufactured and sold at a comparatively low cost, and that it may be readily applied for supporting drawers and other slidably mounted parts.

While I have described the principle of the invention, together with the structure 50 which I now consider the preferred embodiment thereof, it is to be understood that the structure shown is merely illustrative and that such changes may be made, when desired, as fall within the scope of the invention as claimed.

I claim:

1. A bearing of the character set forth, comprising a casing open at its upper end, and having flat sides, a plate secured within 55 the casing and of angular formation in cross section, the plate presenting race elements inclining downwardly from its longitudinal center to the sides of the casing and cooperating with the sides to provide races, 60 anti-friction balls arranged in the races, and

maintained thereby in straight parallel rows, and a roller arranged upon the anti-friction balls with its upper portion extending above the upper end of the casing.

2. A bearing of the character set forth, 70 comprising a casing open at its upper end and provided with flat sides, a plate of angular formation in cross section and arranged within the casing, the plate being provided with upwardly extending end portions and presenting race elements extending downwardly from its longitudinal center to the sides of the casing to provide races, anti-friction balls arranged in the races between the ends of the plate and supported thereby in straight parallel rows, and a roller mounted on the anti-friction balls 80 with its upper side extending above the upper end of the casing.

3. A bearing of the character set forth, 85 comprising a casing open at its upper end and provided with flat sides, a plate of angular formation in cross section and arranged within the casing, the plate being provided with upwardly extending end portions and presenting race elements extending downwardly from its longitudinal center to the sides of the casing to provide races, anti-friction balls arranged in the races between the ends of the plate and supported thereby in straight parallel rows, a roller mounted upon the anti-friction balls 90 with its upper side extending above the upper end of the casing, and means holding the roller against upward displacement 95 from the casing.

4. A bearing of the character set forth, 100 comprising a casing open at its upper end and provided with flat sides, a plate of angular formation in cross section and arranged within the casing, the plate being provided with upwardly extending end portions and presenting race elements extending downwardly from its longitudinal center to the sides of the casing to provide 105 races, anti-friction balls arranged in the races between the ends of the plate and supported thereby in straight parallel rows, a roller mounted upon the anti-friction balls 110 with its upper side extending above the upper end of the casing, the roller being provided in its ends with recesses, and lugs carried by the ends of the casing and loosely fitting in the recesses to hold the roller against upward displacement from the casing. 115

5. A bearing of the character set forth, 120 comprising a casing open at its upper end and provided with flat sides, a plate of angular formation in cross section and arranged within the casing, the plate being provided with upwardly extending end portions and presenting race elements extending downwardly from its longitudinal center to the sides of the casing to provide 125

races, anti-friction balls arranged in the races between the ends of the plate and supported thereby in straight parallel rows, a roller mounted upon the anti-friction balls with its upper side extending above the upper end of the casing, the roller being provided in its ends with recesses, lugs carried by the ends of the casing and loosely fitting in the recesses to hold the roller against upward displacement from the casing, the casing being of elongated rectangular formation in plan, and a substantially elliptical flange extending outwardly from the upper end of the casing and having a flat end arranged in close proximity to the adjacent end of the casing.

In testimony whereof I hereunto affix my signature.

BRADLEY HOAL.
